United States Patent Office

Des. 191,998
Patented Dec. 26, 1961

191,998

WRITING INSTRUMENT

Donald W. Doman, Janesville, Wis., assignor to The Parker Pen Company, Janesville, Wis., a corporation of Wisconsin

Filed June 5, 1961, Ser. No. 65,467

Term of patent 14 years

(Cl. D74—17)

FIG. 1

FIG. 3

FIG. 1 is a side, elevational view of a writing instrument, embodying my new design;

FIG. 2 is an enlarged, top end view of the writing instrument shown in FIG. 1; and

FIG. 3 is an enlarged, bottom end view of the writing instrument shown in FIG. 1.

I claim:

The ornamental design for a writing instrument, as shown.
